UNITED STATES PATENT OFFICE

169,750

ASH TRAY OR SIMILAR ARTICLE

Martin J. Hinterschied, Columbus, Ohio

Application April 25, 1952, Serial No. 19,470

Term of patent 14 years

(Cl. D85—2)

To all whom it may concern:

Be it known that I, Martin J. Hinterschied, a citizen of the United States of America and a resident of Columbus, in the county of Franklin and State of Ohio, have invented a new, original, and ornamental Design for an Ash Tray or Similar Article, of which the following is the specification, reference being had to the accompanying drawing, forming a part hereof.

Figure 1 is a perspective view of an ash tray or similar article showing my new design;

I claim:

The ornamental design for an ash tray or similar article, substantially as shown.

MARTIN J. HINTERSCHIED.
